GAME BOARD

Dorothe Lundgren, Fontana, Calif.

Application April 3, 1948, Serial No. 145,509

Term of patent 7 years

(Cl. D34—5)

To all whom it may concern:

Be it known that I, Dorothe Lundgren, a citizen of the United States, and resident of Fontana, county of San Bernardino, State of California, have invented a new, original, and ornamental Design for a Game Board, of which the following is a specification, reference being had to the accompanying drawing, forming a part thereof, in which:

Fig. 1 is a top plan view of the game board, showing my new design; and

Fig. 2 is an end elevational view thereof.

The side of the game board opposite to that shown in Fig. 1 is plain and unornamented.

I claim:

The ornamental design for a game board, substantially as shown and described.

DOROTHE LUNDGREN.
